Inventor
David L. Boyer,

By Clarence A. O'Brien
Attorney

UNITED STATES PATENT OFFICE.

DAVID L. BOYER, OF READING, PENNSYLVANIA.

COMPOUND TOOL.

Application filed May 1, 1924. Serial No. 710,351.

To all whom it may concern:

Be it known that I, DAVID L. BOYER, a citizen of the United States, residing at Reading, in the county of Berks and State of Pennsylvania, have invented certain new and useful Improvements in a Compound Tool, of which the following is a specification.

This invention relates to new and useful improvements in compound tools and has for its principal object to provide a simple and efficient device which may be used as a claw for removing nails, a hammer, a chisel, wrecking bar or the like, all of the tools being formed in such a manner as to provide a unitary structure.

A further object of the invention is to provide a compound tool of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

30 Figure 1 represents a side elevation of my improved tool with parts shown in section.

Figure 2 is a top plan view thereof, and Figure 3 is a bottom plan view thereof.

35 In the drawing wherein for the purpose of illustration is shown the preferred embodiment of my invention, the numeral 1 designates the shank of the tool, the forward end of which is provided with an offset portion 2, the outer end of which terminates into the upwardly curved portion 3.

40 This upwardly curved portion has a notch 4 formed in the upper edge thereof to provide a claw or nail puller. The shank and offset portion are substantially circular in cross section, the same being formed of any suitable material, preferably steel, while the upwardly curved portion 3 is flattened as clearly shown in Figures 2 and 3 of the drawing.

45 Extending downwardly from the offset portion 2 adjacent the forward end of the

shank 1 is the extension 5, the same being substantially solid and having its bottom face adapted to provide a hammer head 6. 55 The bottom face of the extension 5 is slightly curved and provides a bearing surface for cooperation with the nail puller formed on the outer end of the offset portion 2 when the latter is in use.

60 The extension 5 is further provided with the rearwardly arranged claw portion 7, similar to the claw portion 3 for providing an additional nail puller to be used in places which are not easily accessible by the claw 65 member 3.

65 Arranged on the upper portion of the forward end of the shank 1 is the tapering projection 8, the construction of which is clearly illustrated in Figures 1 and 2 of the drawing. The purpose of this projection is to provide a means for use as a wrecking tool or in opening boxes or the like.

70 The rear end of the shank 1 terminates in the flattened portion 9, the edge of which is sharpened as shown at 10 to provide a cutting chisel and the same is somewhat curved as shown in Figure 1. For the purpose of enabling the use of the chisel, a hammer or the like may be driven against the forward 75 end of the shank at the point illustrated at 11, so as to facilitate the proper use of the tool when used as a chisel.

75 It will thus be seen from the foregoing description, that a compound tool has been 80 provided wherein a number of tools are constructed in such a manner as to provide a unitary structure, the parts being further arranged as not to interfere with the use of each other. Furthermore the simplicity in 85 which my device is constructed enables the same to be manufactured at a very low cost and will further be strong and durable.

85 While I have shown the preferred embodiment of my invention, it is to be understood that various changes in the shape, size 90 and arrangement of parts may be resorted to without departing from the spirit of the invention and the scope of the appended claim.

95 Having thus described the invention, what I claim is:—

100 A tool comprising a shank having at one end a work engaging edge and provided at

the opposite end with an offset curved portion, the shank being provided at one side and at the point of merger with the offset portion, with a laterally disposed projection and having at its opposite side and at the inner end of the offset portion a laterally disposed extension, the said projection and extension being provided at their edges toward the offset portion with plane surfaces, which are disposed outwardly beyond the 10 opposite sides of the outer end of the curved offset portion.

In testimony whereof I affix my signature.

DAVID L. BOYER.
